(57) **CLAIM**

The ornamental design for a sleeping can, as shown and described.

DESCRIPTION

FIG. 1 is a left side view of a sleeping can showing my new design;

FIG. 2 is a right side view thereof;

FIG. 3 is a top view thereof;

FIG. 4 is a front view thereof;

FIG. 5 is a back view thereof; and,

FIG. 6 is a cross section view thereof, taken along line 6—6 of FIG. 3.

The broken lines shown in FIGS. 1, 2 and 4—6 are included for the purpose of illustrating portions of the sleeping can and form no part of the claimed design.
